Application July 18, 1932, Serial No. 623,268

24 Claims. (Cl. 72—1)

Our invention relates to an improvement in the construction of buildings and its object is to provide a simplified fireproof building construction.

In our invention we employ sheet metal forms which can be filled with concrete forming studs which take the place of the ordinary studding; the forms can be easily and quickly erected and assembled by unskilled labor and will result in a great saving in the cost of construction. We also provide novel means for supporting flooring; and novel means for attaching outer and inner walls to the studding. Other novel features of the invention and novel details of construction will be hereinafter pointed out.

15 In the accompanying drawings we have illustrated studding forms such as required for various portions of a building, means for mounting the flooring on the studs and means for attaching inner and outer wall blocks to the studding to form the complete wall and an understanding thereof will enable others to construct buildings from such material. In the appended claims we have summarized the essentials of the invention and novel features of construction and novel combinations of parts for which protection is desired.

15 In the drawings:—

Fig. 1 is a transverse section through one of the novel studs in a straight run of the wall.

30 Fig. 2 is a detail front view partly in section of the stud shown in Fig. 1 with the walls removed.

Fig. 3 is a transverse section through the stud and wall showing the support for a floor beam.

35 Fig. 4 is a vertical section on the line 4—4, Fig. 3.

Fig. 5 is an inner face view partly in section of a complete stud.

40 Fig. 6 is a detail section on the line 6—6, Fig. 3.

Fig. 7 is a sectional view illustrating the connection of a partition wall with the main wall.

Fig. 8 is a sectional view illustrating the stud for the partition wall.

45 Fig. 9 is a sectional view illustrating studding for a corner of a building.

Fig. 10 is a sectional view illustrating a studding for an intersection of walls.

50 Figs. 11 and 12 are detail views of a device for fastening the wall blocks to the studding.

Fig. 13 is an inside face view of a wall block of preferred construction.

55 Fig. 14 is a transverse section of the block on line 14—14, Fig. 13.

Fig. 15 is a transverse section on line 15—15, Fig. 13.

Fig. 16 is an inside face view of a corner block.

Fig. 17 is a side view partly in section of the corner block.

60 Fig. 18 is a transverse section on line 18—18, Fig. 16.

Figs. 19 and 20 are detail sectional views of one form of block fastening device for anchoring the outside wall blocks to the pilaster.

65 Figs. 21 and 22 are sectional top and side views of a form of block fastening device for fastening the blocks to the sheet metal studding.

Fig. 23 is an enlarged transverse sectional view of a stud and part of wall showing the preferred 70 form of block fastening and anchoring device.

Fig. 24 is a detail sectional view of a block showing the preferred anchoring device.

The simplest form of stud is shown in Figs. 1 to 6 and is intended to be used in a straight 75 run of wall. This stud is composed of oppositely faced U-channel members 1 of sheet metal bent so that the flanges of the channel are sprung slightly outward from a right angle position. Between and connecting the channel 1 is a lighter 80 sheet metal container member 2, the side flange of which may be rigidly connected to the channels 1 by some suitable means, such as welding. Placed within the container 2 is a transverse brace 3 of heavier metal. A full length section 85 of stud for a single floor is shown in Fig. 5, brace members 3 being placed at spaced intervals apart throughout the length of this stud. Fig. 5 illustrates the distribution of the braces, beam supports, and slots. Short lengths of angle 5 may 90 be fastened by some suitable means such as welding to the bottom of the stud and by means of these the stud can be fastened to the foundation. As shown the flanges of the side channels 1 are provided with spaced slots 1a for engagement of 95 the wall block attaching devices hereinafter explained.

The members 1 and 2 when erected act as sheet metal forms, bounded on three sides by part 2 and on the fourth side by the outside wall 20, and are to be filled with a building material giving the required anchorage, such as concrete, masonry or the like—thus forming a solid stud or pilaster, which may be reinforced if desired. In the case of the inside wall, there is an air space between the sheet metal form and the interior insulating wall board completely around the building. In Figs. 1, 3 and 7—10 the area to be filled with concrete or similar material in the various forms of studs is filled as indicated at F. 110

It is intended that the outside wall will be positioned before the forms are filled.

Outer wall blocks 20 are shown in Fig. 1 as provided with fastening members 20a which may be hinged to the inner face of the blocks and can be extended at right angles thereto. These members 20a may be entered through the openings 1a (Fig. 2) in the flanges and a fastening wedge 20b dropped through the hole in the member 20a to secure the blocks in place as herein-after described. (See Figs. 11, 12 and 21, 22.) Inner wall blocks 40 may be similarly secured to the other flange by means of similar fastening members 20a. The application of these wall blocks 20 and 40 will be more fully described later.

Between the wall blocks 20 and 40 and the flanges of members 1 may be placed sheets 20x and 40x of an insulating material such as wall board. When the blocks are fastened to the studs, the sprung ends of the flanges of members 1 will bite or dig into the wall board, taking up all play as well as permitting a certain resiliency, so that it is impossible to pull the fastening device from the block.

25 A support 4 for a ceiling or floor beam B, can be located at any desired height in the stud, see Figs. 3 to 6. To facilitate the placing of the floor beams a rectangular hole is cut in part 2 on the side adjacent to the inside wall. It is apparent that when the stud is filled, the area of this hole not taken up by the beam will have to be covered to prevent the filler from running out. A piece of light gauge metal 4x having a hole cut therein the shape of the cross section of the beam, is placed on the beam adjacent the sheet metal member 2, during erection, as shown in Figs. 3 and 4. Reinforcing rods 41 are arranged in the stud and extend each side of the floor beam B, passing through the holes shown in part 4, Fig. 40 3, and coincident holes in the beam, thus producing a rigid connection between the beam and the stud.

To suit requirements of buildings various forms of stud are required, see Figs. 7 to 10. Fig. 45 8 illustrates a stud for a partition wall. In this case parts 1 are the same, but part 2 has its ends inturned as at 2b and a plate 2e is placed therebetween to make an enclosed rectangular form. Part 3 is the same as in Fig. 1. In this case concrete or filler does not come in contact with the wall blocks but is bounded on all four sides by the metal form.

55 Fig. 7 illustrates a stud for the connection of a partition wall with the main wall. In this figure, parts 1 are the same as before described but part 2 has a projecting bend 2a adapted to extend somewhat into the partition wall and a third U-member 1x is attached to this bend to engage the partition wall members as shown. This stud is stiffened by a triangular brace 3d and by transverse ties 3e as shown in Fig. 7.

Fig. 9 illustrates the studding for a corner of a building. Parts 1 are the same but the shape of part 2 is changed as indicated at 2c. The members 1 are disposed at right angles to each other and are connected by a member 2c which is shown as bent into approximately W-shape so that it can turn the corner. The member 2c is stiffened by a diagonal brace 3a fastened at the ends and middle to part 2c. This makes a rigid triangular construction which holds the corner stud form in shape, and this form is further braced by rods or bars 3f, located at intervals determined by the height of the wall slabs, and to bars 3f the corner blocks 30 are fastened.

Fig. 10 illustrates the stud for an intersection of walls where the outside wall turns in the manner shown in the upper left hand corner of the figure, which is the case when a wing is built onto a rectangular house, and partition walls go off towards the interior of the house. In this case the members 1 are constructed as above described but four are used and the member 2 is replaced by a member which is approximately bent into cruciform shape so that it has an angular member 2d projecting into the space between each of the four walls and a member 1 being connected to each of the four projections 2d. The member 2d is interiorly braced by L-shaped bars 3b and straight bars 3c as shown in Fig. 10.

80 After the stud members are erected the exterior walls may be secured thereto. The exterior walls are made of blocks or slabs. These blocks may be made of concrete, but are preferably of "Roselite". However, this stud design is not limited to molded stone blocks, but can be used in conjunction with practically any current building practice.

85 In Figs. 13 to 18 we have indicated generally the preferred form of block and the device for fastening the same as shown in Fig. 13. The blocks 20 for the outside wall are designed with a lap on all four edges to facilitate weather proof construction. A coating C of resinous material (Fig. 19) is preferably placed on the meeting edges of the blocks which acts as a buffer between the blocks, and also to seal the joint. This resinous or plastic material can be put in a fabric such as lamp wick, so as to insure its adhesion and uniformity of thickness.

90 The blocks 20 for the outside wall preferably have a reinforcing wire mesh as 21 molded therein. A series of shallow, vertical grooves 25 may be formed on the inside faces of the blocks in the areas that come in contact with the stud; these grooves tend to make a more rigid construction by providing more irregular surface contact with the filler.

95 For the corners, blocks 30 (see Figs. 16-18) are used. One end of the block 30 may be provided with dowel pins 30c (see Fig. 9) to hold it in place with the adjacent block 20 (see Fig. 9). The other end of this block can be held in place by stud bolts 30d which engage nuts 30b embedded in the block (see Figs. 9, 16, 18), the bolts 115 30d engaging the member 3f to fasten the corner blocks to the stud, see Fig. 9.

100 Figs. 11, 12, 21 and 22; show fastening devices in the blocks. As shown in Figs. 11, 12; and 21, 22 the fastening devices comprise a lug 130 22 which is hinged in a recess of the block 40 to the reinforcing wire and for transport lies concealed in the recess as indicated in dotted lines in Fig. 13. This lug is adapted to be turned out at right angles to the block and can be entered in the slots 1a in the channel 1 and secured by means of a wedge 23 inserted through an opening in the lug. These fastening devices all show more clearly in Figs. 21 and 22.

105 When the block is manufactured this lug lies flush with the back surface of the block, see Fig. 15, and is shipped in this condition: On the job, this lug is pried up and swung to a position at right angles in the manner shown.

110 It is desirable to firmly anchor the blocks 20 to the studs and for this purpose in addition to the fastening devices already described we preferably provide the blocks at their ends with anchoring members such as indicated at 21c in Figs. 1, 23 and 24. These members are prefer-

ably formed by having the end or ends 21c of the reinforcing mesh 21 bent so as to appear on the surface of the block and extend along flush with the surface for a short distance within that

5 area of the block opposite the stud as shown in Fig. 23. The anchor members 21c remain in this position until the block is ready to be placed in the wall, then these wires are bent to a position perpendicular to the face of the block. When
10 the blocks are attached to the stud by lugs 22 these members 21c project into the stud mold formed by the members 1, 2 and walls, and when the stud is filled with concrete, or other suitable filler, the members 21c are permanently anchored
15 in the concrete and thus lock the outer wall blocks to the studs to form a very rigid wall construction.

Figs. 19 and 20 show another means for anchoring the blocks to the studs. In this case L-shaped anchors 22a are hinged to the ends of the
20 block. These lie flush with the block surface until used, then they are pried out and extend into the stud and are anchored in the concrete when the form is filled—thus securing the block permanently to the stud and making the structure very rigid. These L-shaped anchors 21c or
25 22a are intended to extend into the space left for the pilaster and become an integral part of the pilaster when the form is filled, thus locking the blocks of the outer wall permanently to the
30 pilasters; and it is very apparent that such construction would tend to make a very rigid wall, as any strain on the wall would throw an innumerable number of these rods into shear. However, it is also apparent that there must be some means
35 of fastening the block to the metal form before the pilaster is poured, thus necessitating the use of a fastening device such as illustrated in lug 22.

The blocks could be made according to the requirement of the wall and distance apart of the
40 studs. The blocks herein illustrated will enable anyone skilled in the art to make suitable blocks of proper size and dimensions.

By this invention we have provided sheet metal forms containing channels 1 fastened by some
45 suitable means such as welding to containers 2 to make metal forms for the studs and which forms are left in place in the building. Conductivity of heat and cold is reduced throughout by the air spaces, which prevent direct transmission of
50 heat and cold from the outer wall to the inner wall. These air spaces may be filled with an insulating material such as rock wool or the like in order to break up any currents of convection which might occur in a large air space.

55 The construction shown provides multiple layers of wall material, the outside and inside layers 20 and 40 being the finish; and interior layers 20x and 40x being non-conductive of heat or cold. The lack of conductivity is also enhanced by the dead air spaces and insulating filling. This construction not only aids in eliminating transmission of heat and cold but also aids in excluding outside noises and renders the interior of the building very quiet. The spaces between studs can be used advantageously for placing windows.

This construction provides a very rigid structure with a very small amount of metal tonnage and a very small amount of concrete or binding
70 material is required in the studs. It provides novel and rapid means for securing the outside and finishing blocks or walls to the studs. The corrugations in the ends of the blocks adjacent the stud make very rigid, non-weaving joints. The elimination of mortared joints and the use

of a cushioning material at the joints lessens danger of chipping the edges of the blocks, eliminates labor necessary for mortar joints, and at the same time secures a perfect weather seal.

The spaces between adjacent studs can be utilized for utilities such as hot air ducts, water pipes, steam pipes, electric wires, air conditioning in the house, etc. and inside slabs can be made removable for the inspection of the various utilities where desired.

We claim:—

1. In a building, a stud comprising metal members having flanges for engagement with the walls; and a metal container member interposed between the first said members and connected thereto and forming therewith a mold for a concrete filler; and wall blocks having anchoring members on their ends adapted to project into the stud mold and be embedded in the concrete
85
90
95
filler.

2. In a building, a stud comprising metal members having flanges for engagement with and attachment to the walls, a metal container member interposed between the first said members and connected thereto, and wall blocks having fasteners engaging the channel members and forming therewith a mold for a concrete filer; said wall blocks having anchoring members on their ends projecting into the stud and embedded in
100
105
110
the concrete filer.

3. In a building; a stud comprising metal members having flanges for engagement with and attachment to the walls; a metal container member interposed between the first said members and connected thereto, said stud having openings in the flanges of the channel members, and wall blocks having fasteners projecting therefrom and entered through the openings in the channel members and forming therewith a mold for a concrete filer; said blocks having anchoring
115
120
125
members on their ends projecting into the stud and embedded in the concrete filer.

4. A stud comprising oppositely facing spaced metal members having outwardly projecting flanges adapted to extend parallel with the walls

- forming therewith a mold, spaced transversely disposed braces within the container and connected therewith, and a concrete filler in said mold.
5. 11. In a building, studs comprising oppositely facing spaced channel members having flanges extending parallel with the walls, a metal container member interposed between the said channel members and connected therewith, and wall members secured to the flanges of the channel members.
10. 12. In a building, studs comprising opposite spaced channel members having flanges for engagement with and attachment of wall members of the building and extending parallel with the walls, a metal container member interposed between the said channel members forming a mold for concrete or other plastic filler, transversely disposed braces within the container, and wall members attached to the flanges of the channel members.
15. 13. A stud for buildings, comprising spaced oppositely facing channel members having their flanges extending outwardly parallel with the walls of the building, a metal container member interposed between the said channel members and connected therewith to form a mold, transversely disposed braces within the container, a floor beam support secured transversely of and within the metal container member, and reinforcing rods extending through said support.
20. 14. A partition wall stud comprising spaced metal channel members having outwardly extending flanges, a metal container member interposed between the said channel members and having flanges on its ends, and a metal sheet interposed between the container flanges to close the open side of the container.
25. 15. A stud as set forth in claim 14 having transversely disposed braces within the container.
30. 16. A stud for a partition wall connection; comprising oppositely facing spaced channel members having flanges, a metal container member interposed between the said channel members and having a rectangular projection intermediate the side adjacent the partition wall, and a third channel member attached to said projection.
35. 17. A stud as set forth in claim 16 having transversely disposed braces within the container.
40. 18. A corner stud comprising a plurality of spaced channel members having flanges for attachment of the walls of the building, and a metal container member interposed between the said channel members and connected therewith, said container member being bent into approximately W-shape and the channel members being disposed at approximately right angles to each other. 80
45. 19. A stud as set forth in claim 18 having brace bars connected with the channel member and projecting at the opposite side thereof for the attachment of corner blocks. 90
50. 20. A stud as set forth in claim 18 having a diagonal brace connecting the ends of the container member. 95
55. 21. In combination with a corner stud as set forth in claim 18, outer wall blocks secured to the channel members and disposed at right angles to each other, and a corner block interposed between the adjacent ends of said wall blocks and attached to the said bar. 100
60. 22. An intersection stud comprising a metal container member bent into approximately cruciform shape, and flanged channel members, one channel member being attached to each projection of the container member with its flanges outermost. 105
65. 23. An intersection stud comprising a metal container member having four spaced bends adapted to project into intersecting walls, a channel member attached to each projection of the container member and having outwardly projecting flanges, and braces within the container member connecting diametrically opposite bends thereof. 110
70. 24. A building having studs, each comprising spaced flanged metal members and a container member assembled to form a mold for a concrete filler; and wall blocks having anchoring members on their ends projecting into the studs and embedded in the concrete fillers and abutting said flanges. 115
